[57] **CLAIM**

The ornamental design for a musical instrument for
pre-school children, as shown and described.

DESCRIPTION

FIG. 1 is a front elevational view of a musical instrument
for pre-school children showing my new design,
the rear view being a mirror image;
FIG. 2 is a side elevational view thereof, the opposite
side being a mirror image;

FIG. 3 is a top plan view thereof; and

FIG. 4 is a bottom plan view thereof.

The electric cord is broken away for ease of illustration.
